CONCRETE FORM.

Application filed June 23, 1925. Serial No. 39,021.

This invention relates to a concrete form, especially designed for molding reinforced concrete fence posts and the like.

The general object of the invention is to provide a form which is strong and rigid, which will not warp from moisture or continued use, and which may be easily assembled or disassembled by anyone in a very short time, whereby it is possible to produce posts of a uniformly high quality at a minimum cost. Novel means are provided for securing the different parts of the form in assembled relation, and for securing the reinforcing rods and the various devices for attaching wire to the posts. The same mold with suitable removable parts and attachments may be optionally used for molding common posts for the major portion of the fence, double-size brace posts to be used near the corners or ends of the fence, and specially constructed corner or end posts.

The invention consists further in various details of construction and novel arrangements, which will be more particularly described in connection with the accompanying drawings illustrating the invention.

In the drawings:

Figure 1 is a view, partly in plan and partly in section, illustrating the invention as used for making common posts.

Figure 2 is a vertical longitudinal section taken on the line 2-2 of Figure 1.

Figure 3 is an enlarged vertical transverse section taken on the line 3-3 of Figure 1.

Figure 4 is an enlarged detail section particularly illustrating the manner of attaching the reinforcing rods and the means for forming the bolt holes.

Figure 5 is a section taken at right angles to the plane of Figure 4.

Figure 6 is a view, partly in plan and partly in section, showing one end of the mold as used for making the double-size brace posts.

Figure 7 is a view similar to Figure 6, but showing the use of the extension for making the corner posts with an extended anchoring portion at its lower end.

Figure 8 is a vertical transverse section taken on the line 8-8 of Figure 7.

Figure 9 is a detail sectional view show-

ing the means for clamping and stretching the reinforcing rods.

Figure 10 is a vertical section taken on the line 10-10 of Figure 7.

Figure 11 is a detail section showing a modified form of partition for molding posts with rounded corners.

In carrying out the invention, a suitable platform 1 is provided, which may be made from matched boards or ship-lap and covered with a sheet of asphalt roofing 2, or other suitable material which is impervious to moisture. On this platform are laid the sides 3 of the mold and intermediate partitions 4. The opposed faces of these sides and partitions are provided at the top and bottom with cleats 5 and 6 respectively, and are then covered with sheet iron coverings 7 and 8. The ends of the form are closed by channel-shaped steel plates 9 and 10 respectively, and the ends of the sides and partitions are covered by end caps 11, formed with channels or recesses 12 for receiving cleats 13, which are secured to the steel end plates and serve to fix the sides and partitions of the mold in position. As shown in Figures 1, 5 and 6, these cleats 13 are so arranged that the partitions converge toward the upper end, thus forming posts which taper from the bottom to the top.

The end plates 9 and 10 are secured and held in assembled relation by means of hooks 14, which are engaged with holes in the ends of the plates, and are connected with the adjacent portions of the sides 3 by strong coil springs 15. After the sides, partitions and end plates of the mold have been assembled, reinforcing rods 16 are placed in position before the concrete is poured. Each of these reinforcing rods is approximately in the shape of a hair-pin with the intermediate bent portion 17 located at the upper end of the post. One of these hair-pin shaped rods is provided for each common post, and two for each double post. The plate 9 is pressed inwardly, as shown at 18, where the top of each post comes, and is formed with a slot 19 for receiving the bent portion 17 of the reinforcing rod. After the bent portion of the rod has been inserted in the slot, a nail

20, or similar means, may be passed through the same, as shown in Figures 4 and 5. The edges of the slot 19 are preferably turned under to form lips 21, thus making 5 it easier to insert or remove the nail.

The rod tightener comprises a U-shaped member 22, the extremities of which are curved downwardly, as seen at 23 in Figure 9, and are adapted to bear against the outer 10 face of the end plate 10. The legs of the member 22 are connected by a transverse pin 24, on which is pivoted a dog 25 having a slot 26 adapted to receive the end of the reinforcing rod 16. The latter is adapted 15 to project through a hole in the plate 10 and through the slot 26 in the dog, and the dog is preferably made of hardened steel, and the side of the slot 26 sharpened so as to firmly engage the rod. The slot 26 may 20 be tapered so as to fit rods of different sizes. It will be understood that a tightening member 22 is provided for each of the projecting ends of each rod 16.

Before the concrete has set in the mold, 25 a number of transverse rods 28 are inserted, as shown in Figure 4, to be later withdrawn so as to provide bolt holes. It will be understood that each post is provided with as many bolt holes as there are strands of wire 30 to be attached to the post. The rod 28 has a lug 29 secured thereto so as to provide an arcuate recess in the face of the post, in order that the bolt which secures the fence 35 wire may draw the latter into the recess, and by its frictional engagement therewith hold the wire more securely. The outer end of the rod 28 is provided with a handle 30, so that it may be withdrawn from the post when the latter has become sufficiently 40 set.

The invention as shown in Figures 1 to 5 inclusive, is used for making common posts 31, which are octagonal in cross section. The plates 9 and 10 project somewhat above the posts, and the side pieces 3 also have extensions 32 secured thereto, so as to prevent spilling of the concrete 45 while it is being tamped into the mold. In the embodiment illustrated, provision is 50 made for making five common posts at one time, or by arranging the mold as shown in Figure 6, two double size or brace posts 33 may be made at the same time. In making 55 the brace posts, the first and last partitions are left out, and the center mold is left empty, as shown in Figure 6.

For making a corner or end post 34, as shown in Figures 7 and 10, an extension is 60 connected to the lower end of the mold used in Figure 6. This extension comprises opposed side walls 35 connected by brace bars 26, and having at their lower ends offset portions 37 for forming an anchor portion 65 38 for the post. The upper ends of the side pieces 35 are inserted in the correspond-

ing recesses or channels 12 formed at the lower ends of the sides 3 and partitions 4 respectively, and the lower ends of the offset portions 37 of the side pieces 35 are secured in a supplemental end plate 39, 70 which is provided with holes for receiving lugs 40 formed on the lower ends of the side pieces. The plate 39 is held on the lower ends of the side pieces by hooks 14 and springs 15, in the same manner as the 75 end plates 9 and 10 are held. For reinforcing the corner posts, rods 16^a are used which are longer than the rods 16, to correspond with the length of the post.

The form may be provided with interchangeable pieces and partitions of different shape to mold posts of any shape desired. For example, I have shown in Figure 11 a partition 41, having cleats 42 with concave faces, and covered with sheet iron 85 coverings 43 to form posts with rounded corners. It is also apparent that the mold may be used for molding such other articles as are desired.

It is to be particularly noted that the 90 form may be very quickly assembled, merely by laying the side pieces and partitions on the platform and hooking the end plates in place. As the reinforcing rods are placed in position, the tightening member 95 22 may be quickly attached to draw the rods up tightly, and this also aids in holding the end plates tightly in place while the form is being used. The sides and partitions are preferably made of wood covered 100 with sheet metal, so that they are very strong and rigid, and will not warp from use or moisture. Experience is not necessary for anyone to be able to use the form, and the 105 posts may be made with a minimum expenditure of time and labor.

In building a fence with concrete posts made by means of this mold, the longer post 34 with its anchor base 38 will generally be used at the corners and for gate 110 posts. The extended portion is approximately eighteen inches long, so that it provides a very firm base. Adjacent this post, the double-brace posts 33 may be used, and the remainder of the fence constructed with 115 common posts 31.

While I have shown and described specifically one embodiment of the invention, it is to be understood that this is merely 120 for the purpose of illustration and that various changes may be made in the size, shape and relative arrangement of the various parts without departing from the scope of the invention as expressed in the claims.

What is claimed is:

1. A form for molding concrete and the like, comprising longitudinal walls and end plates provided with projections and recesses which cooperate to fix the relative 125 positions of said walls and end plates when 130

- the latter are held against the ends of the walls, yieldable means for initially holding the end plates in position, reinforcing rods adapted to be placed longitudinally of the form, and means for engaging and tightening said rods and at the same time rigidly securing said end plates.
2. A form for molding concrete and the like, comprising longitudinal walls and end plates provided with means for fixing the relative positions of the walls laterally when the plates are held against the ends of the walls, yieldable means for initially holding the end plates in that position, reinforcing rods adapted to be placed longitudinally of the form, and means for engaging and tightening said rods and at the same time rigidly securing said end plates.
3. A form for molding concrete and the like, comprising longitudinal walls and end plates provided with means for preventing lateral movement of said walls when the plates are held against the ends thereof, reinforcing rods adapted to be placed longitudinally of the form with their ends projecting through the end plates, and rod tighteners having means to engage and clamp the ends of said rods, each tightener having its inner position curved downwardly and adapted to exert increasing pressure against the outer face of the end plate as the outer portion of the tightener is swung downwardly to tighten the rod.
4. A form for molding concrete and the like, comprising longitudinal walls and end plates provided with means for fixing the relative position of the walls laterally when the plates are held against the ends of the walls, hair-pin shaped reinforcing rods adapted to extend longitudinally from end to end of the mold, means for attaching the curved portions of the rods to one of the end plates, the other end plate having holes through which the ends of the rods project, and rod tighteners having means for engaging and holding the projecting ends of the rods and for exerting pressure against the outer face of the adjacent end plate.
5. A form for molding concrete and the like, comprising longitudinal walls and end plates provided with means for preventing relative lateral movement of the walls when the end plates are held against the ends of the walls, yieldable means for initially holding the end plates in that position, hair-pin shaped reinforcing rods adapted to extend longitudinally from end to end of the mold, means for attaching the curved portions of the rods to one of the end plates, rod tighteners engageable with the outer face of the other end plate, and having means for engaging and holding the ends of the rods and for exerting pressure against the end plate to tighten said rods.
6. A form for molding concrete and the like, comprising longitudinal walls and end plates provided with means for preventing relative lateral movement of the walls when the plates are held against the ends of the walls, yieldable means for initially holding the end plates in that position, hair-pin shaped reinforcing rods adapted to extend longitudinally from end to end of the mold, one of the end plates having inwardly pressed portions provided with slots through which the curved portions of the rods may be projected and pinned, the other end plate having holes through which the ends of the rods project, and a rod tightener for each of said ends, said tightener having means to clamp the end of the rod, and means for exerting increasing pressure against the outer face of the adjacent plate to tighten said rod.
7. A form for molding concrete and the like, comprising longitudinal walls and end plates provided with means for preventing lateral movement of the walls when the plates are held against the ends of the walls, hair-pin shaped reinforcing rods adapted to extend longitudinally from end to end of the mold, means for attaching the curved portions of the rods to one of the end plates, the other end plate having holes through which the ends of the rods project, and a rod tightener for each of said ends, said tightener comprising a U-shaped member with a dog pivoted between its legs, said dog having a tapered slot to engage and hold the end of the rod, the terminal portions of said legs being curved downwardly and adapted to exert increasing pressure against the outer face of the adjacent end plate and tighten the rod as the U-shaped member is swung downwardly.
8. A form for molding concrete and the like, comprising longitudinal walls and end plates provided with means for preventing relative lateral movement of the walls when the plates are held against the ends thereof, yieldable means for initially holding the end plates in that position, hair-pin shaped reinforcing rods adapted to extend longitudinally from end to end of the mold, one of the end plates having inwardly pressed portions provided with slots through which the curved portions of the rods may be projected and pinned, the other end plate having holes through which the ends of the rods project, and a rod tightener for each of said ends, said tightener comprising a U-shaped member with a dog pivoted between its legs, said dog having a tapered slot to receive and hold the end of the rod, the terminal portions of said legs being curved downwardly and adapted to exert increasing pressure against the outer face of the adjacent end plate and tighten the rod as the U-shaped member is swung downwardly.

9. A rod tightener comprising a U-shaped member having legs between which a dog is pivoted, said dog having a tapered slot to receive and hold the end of a rod, the terminal portions of said legs being curved downwardly and adapted to exert increasing pressure against an abutment to tighten the rod as the U-shaped member is swung downwardly.
10. 10. A form for molding concrete and the like, comprising longitudinal walls, an end plate, cooperating means on the end plate and adjacent ends of the walls to prevent lateral movement of said ends when the plate is held thereagainst, an attachment having walls constituting extensions for said longitudinal walls at their other ends, coengaging means to prevent relative lateral movement of the extension walls and the adjacent ends of the first-mentioned walls, means rigidly connecting the extension walls to each other; an end plate for the outer end of the extension, and means for rigidly connecting the same to the extension.
11. A form for molding concrete and the like comprising longitudinal walls, an end plate, means on said end plate and adjacent ends of the walls to prevent lateral movement of said ends when the plate is held thereagainst, an attachment having walls which are adapted to form extensions for said first-mentioned walls at their other ends, coengaging means to prevent relative lateral movement of the extension walls and the adjacent ends of the first-mentioned walls, means rigidly connecting the extension walls to each other, an end plate for the outer end of the extension, and means for rigidly connecting the same to the extension walls to each other, an end plate for the outer end of the extension, and means for rigidly connecting the same to the extension.
12. A form for molding concrete and the like, comprising longitudinal walls, an end plate cooperating with said walls at one end of the mold, an attachment having walls adapted to form extensions for said longitudinal walls at the other end of the mold, co-engaging means to prevent relative lateral movement of the extension walls and the adjacent ends of the first-mentioned walls, means rigidly connecting the extension walls to each other, an end plate for the outer end of the extension, and means for connecting the two end plates to each other and at the same time rigidly securing the end plates to the adjacent ends of the respective walls.

In testimony, that I claim the foregoing as my own, I have hereto affixed my signature.

HERMAN F. SCHNEIDER.
